Inventor
Leon Ottlinger,
C. P. Goepel.

UNITED STATES PATENT OFFICE.

LEON OTTINGER, OF NEW YORK, N. Y.

PROTECTING DEVICE FOR LATCH PARTS.

Application filed October 22, 1920. Serial No. 418,706.

To all whom it may concern:

Be it known that I, LEON OTTINGER, a citizen of the United States, and a resident of the city of New York, in the county 5 and State of New York, have invented certain new and useful Improvements in Protecting Devices for Latch Parts, of which the following is a description.

This invention relates to an improved protecting means for latch parts and generically considered contemplates the provision of a simply constructed device for application to the exposed part of a latch which has been applied to a door so as to 10 permit of the proper painting or varnishing of the door while preventing the collection of the paint or varnish upon parts of the latch.

It is the primary object and purpose of 20 the present invention to provide a device for the above purpose which may be inexpensively produced in blank form by cutting or stamping a metal sheet, and then subsequently bending and shaping the blank 25 for proper application to the latch part.

More specifically, I propose to provide a detachable protecting device of this character having means to frictionally co-act with the latch part thereby and hold the 30 device against accidental displacement and insure the complete protection of all surfaces of the latch part upon which the paint or varnish would be liable to collect.

With the above and other objects in view, 35 the invention consists in the improved form and construction of the protecting device as will be hereinafter more fully described, illustrated in the accompanying drawing and subsequently incorporated in the subjoined claims.

In the drawing wherein I have illustrated several desirable and practical embodiments of the invention and in which similar reference characters designate corresponding 45 parts throughout the several views,

Figure 1 is a side elevation of the edge portion of a door having a latch applied thereto and illustrating one embodiment of the protector applied to the projecting part 50 of the latch mechanism;

Figure 2 is a horizontal sectional view;

Figure 3 is a plan view of the blank from which the protecting device is formed;

Figure 4 is a perspective view of the completed protector;

Figure 5 is a perspective view illustrat-

ing another embodiment of the invention.

Figure 6 is a plan view of the blank from which the device shown in Figure 5 is formed.

Figure 7 is a fragmentary horizontal section through the door frame illustrating another form of the protector applied to the lug or projection on the strike plate;

Figure 8 is a section taken on the line 65 6-6, Figure 5;

Figure 9 is a similar view of the protector in its normal condition and

Figure 10 is a plan view of the blank from which the protector shown in Figure 70 5 is formed.

Referring in detail to the drawing and more particularly to Figures 1 to 4 thereof, D designates the edge portion of the door to which a latch of any suitable type 75 is applied. In the manufacture of doors for automobiles, in latches of the latest approved type applied to such doors, the several parts of the latch mechanism have very close coacting engagement and there 80 is little or no play or lost motion between the several parts. It has been found, that when the surfaces of such doors are painted or varnished, the paint or varnish collects upon the exposed parts of the latch mechanism, and finds its way to the interior of 85 the latch casing. The coagulation of the paint or varnish, which is of a highly adhesive nature causes the parts of the mechanism to stick and precludes the free operation of the latch. Heretofore it has been necessary to scrape away this coagulated paint or varnish upon the parts of the latch, and in view of the fact that access to the latch parts is quite difficult, this operation 90 is exceedingly tedious and time consuming.

It is therefore the purpose of my present invention to provide means for protecting the parts of the latch which project from the door or frame surfaces to which the 95 paint is to be applied so that such surfaces can be quickly painted or varnished and the paint excluded from the latch parts, without necessitating the exercise of extreme care.

To this end, I provide a protecting shield formed of sheet steel or other easily bendable material as indicated generally by the numeral 5. This shield is adapted to be engaged over the end of the latch bolt 6 which 110 projects from the edge of the door.

As shown in Figure 3 of the drawings the

device is formed from a blank cut or stamped out of a metal sheet, said blank including the body 7 and the wings 8 projecting laterally from the opposite edges of said body. These 5 wings are integrally connected at their central portions with the body 7 of the blank and at each side of said central portion they are slightly separated therefrom as at 9 so as to be readily bendable without breakage 10 from the body 7 and to also permit of the bending of the body 7 of the shield or protector into the longitudinally curved form seen in Figure 1. One relatively long end portion 10 of the sheet metal blank is adapted 15 to be bent along the dotted line indicated at 11 in Figure 3 to a position substantially at right angles to the body portion 7 of the shield. The other relatively short projecting end portion 12 of the body 7 is adapted 20 to extend over and upon one of the side plates of the latch casing which is flush with the face of the door. It will be noted that one edge of each of the wings 8 is obliquely inclined as at 13 and these inclined edges of 25 said wings which constitute the opposite sides of the shield or protector engage closely against the transversely inclined edge face D' of the door.

In the stamping or cutting of the sheet 30 metal blank a longitudinally extending spring tongue 14 is cut in each of the wings 8, said tongue at one end remaining integral with the wing while the other end thereof is free. These tongues are projected out of the 35 plane of the wings 8 for a purpose which will presently appear.

After the sheet metal blank has been cut or stamped as seen in Figure 3, the body portion 7 thereof is bent into the curved form 40 shown in Figure 1 and the end portion 10 bent along the line 11 until it is disposed in substantially parallel relation to the other end portion 12 of the body 7. The two wings 8 are then bent inwardly and are soldered, welded or otherwise permanently secured along their longitudinal edges and at the edges 9 to the contacting edge portions of the shield body 7 and the end 10 of the blank. With the parts so arranged, the 45 shield or protector presents the appearance seen in Fig. 4 of the drawings. When the door is to be painted or varnished, this shield or protector is slipped over the projecting end portion of the latch bolt 6 until the obliquely inclined edges 13 of the opposite 50 side walls of the shield are engaged with the edge face of the door, and the projecting end or flange 12 of the body wall of the shield is lapped over the side of the latch 55 casing. The spring tongues 14 exert a constant resilient pressure against the upper and lower sides of the latch bolt 6, and serve to prevent the accidental displacement of the shield from its applied position. Paint or 60 varnish can now be freely applied to the 65

edge face of the door with the assurance that any excess of the paint or varnish will not find its way upon the surfaces of the bolt 6 or to the other internal parts of the latch mechanism but will merely collect upon the 70 walls of the shield from which it can be readily removed.

In Figures 5 and 6 of the drawing I have illustrated another embodiment of the invention and one which for reasons of simplicity and economy in manufacture, I deem to be preferable. In this construction the device is formed from a blank sheet of bendable metal 25. This sheet is stamped or cut to provide the parts 26 and 27 which respectively constitute the opposite sides of the protector. From the medial portion of the blank obliquely inclined wings 28 extend laterally and have their end edges disposed in parallel relationship with the longitudinal edges of the portions 26 and 27. In the bending of the blank, as the portions 26 and 27 are bent into parallel relation to each other, the central portion of the blank is disposed at an oblique inclination as indicated at 29 in Figure 5 and the side wings 28 are simultaneously bent inwardly into parallel relation with each other and owing to the obliquity of these wings they will extend in parallel relation between the opposed side 95 portions 26 and 27 and their end edges will be parallel with the inclined medial portion 29. As seen in Figure 5, the wings 28 are unconnected along their longitudinal edges with the portions 26 and 27 so that they are 100 capable of a resilient yielding movement. In this construction the device is properly proportioned in accordance with the dimensions of the latch bolt so that it will snugly 105 fit thereover. In fact, the wings 28 must be slightly deflected outwardly from their normal positions in order to insert the protector over the projecting end of the latch bolt. Thus these wings tending to return to their 110 normal positions exert a constant frictional pressure against the latch bolt and thereby serve to positively retain the device in its applied position and against accidental displacement. In this form of the protector, the projecting flange 12 as above referred to 115 in connection with the construction first described is not necessary as the free end edges of the several parts 26, 27 and 28 of the protector will tightly fit against the wall of the latch casing. Thus the paint may be readily applied to all of the exterior surfaces of the 120 casing wall and without liability of any of the paint collecting on the surfaces of the latch bolt.

In Figures 7 to 10 inclusive of the drawings, I have shown another form of the shield or protector which is designed for application to the lug or projection 15 on the strike plate which is fixed to the door frame. As is usual, this lug is provided 130

with an obliquely inclined face 16 against which the rounded or convex end of the latch bolt 6 rides as the door is moved to its closed position. In this form of the 5 shield or protector, the device is produced from the blank shown in Figure 8 consisting of a sheet metal plate 17 one end portion 18 of which is adapted to be bent along the line 19 for engagement upon the end and edges will be parallel with the inclined medial portion 29. As seen in Figure 5, the wings 28 are unconnected along their longitudinal 10 edges with the portions 26 and 27 so that they are capable of resilient yielding movement. In this construction the device is 15 properly proportioned in accordance with the dimensions of the latch bolt so that it will snugly fit thereover. In fact, the wings 28 must be slightly deflected outwardly from 20 their normal positions in order to insert the protector over the projecting end of the latch bolt. Thus these wings tending to return to their normal positions exert a constant frictional pressure against the latch 25 bolt and thereby serve to positively retain the device in its applied position and against accidental displacement. In this form of the protector, the projecting flange 12 as above referred to in connection with the construction 30 first described is not necessary as the free end edges of the several parts 26, 27 and 28 of the protector will tightly fit against the wall of the latch casing. Thus the paint may be readily applied to all of 35 the exterior surfaces of the casing wall and without liability of any of the paint collecting on the surfaces of the latch bolt. In view of the fact that the edges of the several sides of the protector engage the face 40 of the latch casing closely adjacent to the latch bolt, it will not be necessary to re-touch the painted surface in order to fully cover or coat the same, as would be the case if the protecting device had its walls spaced 45 from the surfaces of the latch bolt.

In Figures 7 to 10 inclusive of the drawings, I have shown another form of the shield or protector which is designed for application to the lug or projection 15 on the 50 strike plate which is fixed to the door frame. As is usual, this lug is provided with an obliquely inclined face 16 against which the rounded or convex end of the latch bolt 6 rides as the door is moved to its closed position. In this form of the shield or protector, the device is produced from the blank shown in Figure 10 consisting of a sheet metal plate 17 one end portion 18 of which is adapted to be bent along the line 19 for engagement upon the end face of the lug or projection 15. The remaining portion of the plate 17 is provided upon each of its longitudinal edges with a flange 20. Normally, these flanges are slightly inclined inwardly in convergent relation to each other

as seen in Figure 9. Thus it will be apparent that when the device is applied as in Figure 7, the flanges 20 are sprung outwardly from their normal positions until they are at right angles to the body plate 17 so that they 70 exert a frictional gripping engagement against the upper and lower surfaces of the lug 15 and thereby retain the shield or protector in its applied position. The paint or varnish can now be readily applied to the 75 door frame without liability of coating the surfaces of the strike lug 15 with which the bolt coacts.

From the foregoing description considered in connection with the accompanying drawing, the construction and manner of use of the several embodiments of the invention herein referred to will be clearly understood. The shields or protecting devices can be easily and quickly applied to the exposed 80 latch parts and also readily removed after they have served the intended purpose. By means of the present invention, the proper operation of the latch mechanism will be positively assured and the additional labor 85 and loss of time heretofore incident to the necessity of removing the coagulated paint or varnish from the parts of the latch is entirely obviated. It will also be appreciated that in view of the very simple form 90 and construction of the invention, the device can be manufactured at very small cost and therefore will not add materially to the expense involved in the equipment of automobile or other doors with the latch mechanism. 100

I have herein referred to several embodiments of the improved shield or protector which I have found to be very satisfactory and desirable in practice, but it will nevertheless be understood that the device is susceptible of many minor modifications and I therefore reserve the privilege of resorting to all such legitimate changes as may be fairly embodied within the spirit and scope 110 of the invention as claimed. 105

I claim:

1. A protecting device as described comprising a hollow body shaped to the general configuration of the projecting part of a 115 latch bolt when in normal projected position and adapted to cover the same on all sides.

2. A protecting device comprising a hollow casing shaped to the general configuration of the projecting part of a latch bolt when in normal projected position and extending about on all sides and on the end of the latch bolt, said casing adapted to frictionally engage the projecting portion 120 of the bolt to hold the same against creeping of being accidentally moved away from the lock casing. 125

3. A shield or protector for the parts of door latches comprising a member open at 130

- one side to receive the projecting end of a latch bolt and the walls of said member closely engaging the edge of the door to thereby prevent the collection of paint upon the surfaces of the latch bolt when the door is painted and means frictionally co-acting with the latch bolt to hold the shield in its applied position and prevent accidental displacement thereof.
10. 4. A shield or protector for the parts of door latches comprising a member open at one side to receive the projecting end of a latch bolt and the walls of said member closely engaging the edge of the door to thereby prevent the collection of paint upon the surfaces of the latch bolt when the door is painted, opposite side walls of the shield or protector having spring tongues to frictionally engage the latch bolt and detachably hold the same in its applied position.
15. 5. A shield or protector for parts of door latches consisting of a member open at one side to receive the projecting end of the latch bolt and completely cover or house the same, one wall of said member being provided with an extension or flange to engage over one side of the latch casing and the other walls of said member closely engaging the edge face of the door adjacent to the latch bolt and preventing the collection of paint upon the surfaces of the bolt when the door is painted.
20. 6. A shield or protector for parts of door latches consisting of a member open at one side to receive the projecting end of the latch bolt and completely cover or house the same, one wall of said member being provided with an extension or flange to engage over one side of the latch casing and the other walls of said member closely engaging the edge face of the door adjacent to the latch bolt and preventing the collection of paint upon the surfaces of the bolt when the door is painted.
25. 7. A shield or protector of the character described comprising a member open at one side adapted to receive and entirely enclose a part of a door latch and the edges of the protector contacting with the latch casing closely adjacent to the several surfaces of the latch part whereby substantially the entire surface of the casing may be painted in one operation and the collection of paint upon the surfaces of the latch part prevented.
30. In testimony that I claim the foregoing as my invention, and have signed my name hereunder.

LEON OTTINGER.
